HARRY B. HULL, OF DAYTON, OHIO, ASSIGNOR TO FRIGIDAIRE CORPORATION, OF DAYTON, OHIO, A CORPORATION OF DELAWARE

HEAT DISSIPATING DEVICE FOR REFRIGERATING APPARATUS

Application filed October 31, 1928, Serial No. 316,253. Renewed June 4, 1932.

This invention relates to refrigerating apparatus particularly to compressors and driving means therefor.

One of the objects of the invention is to provide an improved means for reducing the noise incident to the operation of apparatus of this type.

More specifically it is an object of the invention to inclose the noisy parts of a refrigerating apparatus in a sound absorbing housing and to provide an improved means for dissipating the heat generated within the housing.

Another object of the invention is to provide sound absorbing means of a character indicated which is readily removable from the refrigerating apparatus to permit inspection and adjustment.

More specifically it is an object of the invention to provide a heat transmitting member including a quantity of volatile liquid for conducting the heat from within the housing to the outside atmosphere.

Another object of the invention is to provide improved means for cooling the compressor in arrangements of the character indicated.

Another object of the invention is to provide a sound absorbing housing for inclosing the noisy parts of a refrigerating apparatus and exposing to the atmosphere heat generating parts which do not make noise.

Further objects and advantages of the present invention will be apparent from the following description, reference being had to the accompanying drawing, wherein a preferred form of the present invention is clearly shown.

In the drawing:

40 Fig. 1 is a horizontal section of a refrigerating apparatus constructed in accordance with the invention;

45 Fig. 2 is a vertical section of the apparatus shown in Fig. 1; and

50 Fig. 3 is a vertical section showing the compressor cooling device.

Referring to the drawing 10 designates any suitable base upon which is mounted a compressor 11 and a motor 12 which drives the compressor through a belt 13 and pulley

wheels 14 and 15. Connected to the compressor is a condenser 18 which receives compressed gaseous refrigerant from the compressor, cools and liquefies the refrigerant and discharges the refrigerant to a receiver 55 or reservoir 19. If desired, for the sake of convenience the receiver may be mounted on a pair of brackets 20 supported in the base 10. The brackets 20 also support a housing 22 containing a switch for controlling the 60 motor. Since it is the motor, compressor and switch which make noise in operation, I propose to avoid annoyance by preventing such noise from transmitting from the apparatus itself. This may be accomplished by completely inclosing the noisy parts of the apparatus in a housing which prevents the transmission of sound from the apparatus to distant points. As shown in the drawing this housing may include a base 25 upon which 70 the apparatus is supported, and a housing proper consisting of side walls 26 and a cover 27. The base and housing may be made of any suitable material, preferably some material which absorbs sound waves and prevents the transmission of sound through the housing.

Since the motor, compressor and condenser all generate heat during operation and since this heat must be removed, I provide means 80 for dissipating to the outside atmosphere the heat generated. Since the condenser does not make noise this may be placed outside of the housing where it is cooled by contact with the atmosphere, which cooling may be enhanced 85 by circulating air over the condenser in any desired manner.

Heat conducting members 30 are passed through one of the walls 26 of the housing. The inside ends of the heat conductors are in 90 the path of air circulated by the fan and the outside ends of the heat conductors dissipate the heat to the atmosphere.

In order to increase the heat conducting capacity of the members 30 they are preferably formed as closed chambers containing a volatile liquid such as diethyl ether, pentane, or isopentane. The liquid runs to the lower end of the tubes where it absorbs heat from the air circulated by the fans and is evapo- 100

rated. The vapor rises in the tubes to the cooled ends outside of the housing. The vapor is condensed outside of the housing by the atmospheric temperature and the condensed liquid flows back into the lower end of the tubes. Thus as long as heat is applied to the lower ends the liquid circulates and removes heat from the housing.

This arrangement is particularly advantageous in providing means for cooling the compressor and motor directly. A tube 31 has its lower end thermally attached to some part of the compressor to be cooled, for example to the valve plate 32 ordinarily provided in compressors for carrying the discharge valves. Preferably a hollow chamber 37 is provided in the valve plate 32 in any suitable manner and the tube or tubes 31 communicate with this chamber. This arrangement is shown in the fragmentary vertical section view of the upper part of the compressor, Fig. 3. One manner of cooling the motor is to wrap a hollow jacket 38 about the field frame and connect it with a tube 39. It is of course to be understood that the chamber 37 and jacket 38 contain a quantity of volatile liquid and like the tubes 30, the tubes 31 and 39 conduct vapor to the exterior of the housing where it condenses and returns to the chamber and jacket. It is to be understood that other portions within the housing may be cooled in the same manner as shown with regard to the compressor and motor and that the condensing portion exterior of the housing may be readily increased if desired by increasing the volume of the condensing tubes outside the housing and fins 40 may be added.

In order to provide for the removing of the housing, the cover 27 is made removable from the side walls 26 and the tube 31 is passed through a slot 34 in the upper edge of the heat conducting wall. To remove the housing without disturbing the relation of the heat transmitting members the cover is first removed, after which the tubes 31 and 39 can be bent upwardly through slots formed in the side wall. After that is done, the wall 26 can be removed. Preferably the housing is hermetically sealed to prevent noises created therein from being transmitted to the exterior. Therefore, the slots in the wall 26 may be suitably closed as for example by rubber grommets 42 each having a groove which snugly embraces the opposite sides of the housing wall and each having an opening for receiving the tube. The joint of the walls 26 and base 25 is also sealed by a strip of flexible material such as rubber 41. This strip 41 fits tightly within a groove in base 25 and the upper end thereof is grooved for receiving the lower edge of the housing. Suitable openings are provided in the strip for receiving the refrigerant pipes. The openings through which the tubes 30 extend may be suitably sealed and preferably these tubes

may be secured in place by a bonding material such as solder.

While the form of embodiment of the invention as herein disclosed, constitutes a preferred form, it is to be understood that other forms might be adopted, all coming within the scope of the claims which follow.

What is claimed is as follows:

1. Refrigerating apparatus comprising in combination a compressor, means for driving the compressor, a housing completely inclosing the compressor and driving means, and heat conducting members extending through the housing for transmitting to the outside atmosphere heat generated within the housing, and means for circulating the air confined within the housing over said heat conducting members. 75

2. Refrigerating apparatus comprising in combination a compressor, means for driving the compressor, a housing completely inclosing the compressor and driving means, and heat conducting members extending through the housing for transmitting to the outside atmosphere heat generated within the housing, one of said members being thermally connected to the compressor and means for circulating the air confined within the housing over said heat conducting member. 80

3. Refrigerating apparatus comprising in combination a compressor, means for driving the compressor, a housing completely inclosing the compressor and driving means, and heat conducting members extending through the housing for transmitting to the outside atmosphere heat generated within the housing, said heat conducting members including closed containers for volatile liquid, and means for circulating air confined within the housing over said heat conducting members. 95

4. Refrigerating apparatus comprising in combination a compressor, means for driving the compressor, a housing completely inclosing the compressor and driving means, and heat conducting members extending through the housing for transmitting to the outside atmosphere heat generated within the housing, said heat conducting members including closed elongated containers for volatile liquid, the end of each container in the housing being lower than the end outside the housing, and means for circulating air confined within the housing over said heat conducting members. 110

5. Refrigerating apparatus comprising in combination a compressor, means for driving the compressor, a housing completely inclosing the compressor and driving means, and heat conducting members extending through the housing for transmitting to the outside atmosphere heat generated within the housing, said heat conducting members including closed chambers containing vola- 125

tile liquid, the end of each chamber within the housing being lower than the end outside the housing, means for circulating the air confined in the housing over the lower ends of the heat conducting members whereby the
5 volatile liquid within the heat conducting members will be evaporated.

6. Refrigerating apparatus comprising in combination a compressor, means for driving the compressor, a housing completely enclosing the compressor and driving means, and means for conducting to the atmosphere heat generated within the compressor including a container for volatile liquid thermally connected to the compressor body,
10 means for conducting vapor evaporated within said container outside the housing, means for condensing said vapor outside the housing and returning the liquid to the container.
15

7. Refrigerating apparatus comprising in combination a compressor, a motor for driving a compressor, a housing completely enclosing the compressor and motor, and heat conducting members extending through the housing for transmitting to the outside atmosphere heat generated within the housing, one of said members being thermally connected to the motor, and means for circulat-
25
30 ing the air confined within the housing over said members.

8. Refrigerating apparatus comprising in combination a compressor, means for driving the compressor, said compressor having a cooling chamber therein, a housing completely enclosing the compressor and driving means, and means for conducting through said housing and dissipating to the atmosphere heat generated by the compressor including a volatile fluid in said cooling chamber and a tube extending from said chamber through the housing for condensing the volatile fluid outside the housing and returning the liquid to the chamber.
